HEAT EXCHANGER

George A. Worn, Greenwich, Conn., and George W. Evans, Teaneck, N. J., assignors to The Lummus Company, New York, N. Y., a corporation of Delaware

Application July 31, 1946, Serial No. 687,330

3 Claims. (Cl. 257—221)

1

This invention relates to improvements in heat exchangers of the shell-and-tube type and more particularly to improvements in a leakage interception feature to prevent intermingling of the shell-side fluid and the tube-side fluid.

An important object of the invention is to provide an advantageous combination of a leakage interception feature with means for holding a tube sheet against displacement under an unbalanced pressure.

A further object of the invention is to provide a satisfactory embodiment of such a combination in a heat exchanger of a removable bundle type wherein the tube sheet at one end of a tube bundle is removably seated within a channel or header at one end of the shell and the leakage interception feature is employed to prevent leakage from either the shell or the channel past the edge or margin of the tube sheet.

These and other objects and advantages of the invention will appear from the following description taken in connection with the accompanying drawing.

In the drawing:

Fig. 1 is a vertical sectional view of a heat exchanger unit embodying the invention, the section being taken approximately on the line 1—1 of Fig. 2;

Fig. 2 is a horizontal section on the line 2—2 of Fig. 1; and,

Fig. 3 is an enlarged detail vertical section approximately on the line 3—3 of Fig. 2.

According to the invention, in the embodiment shown, a vertical heat exchanger unit is provided with an enlarged channel or header at the upper end of its shell. Within said channel a tube sheet has its margin seated upon an annular shoulder or ledge at the bottom of the channel, and a tube bundle depends from the tube sheet into the shell. A leakage interception means is located at the periphery of the tube sheet and, in cooperation with said means, there is an abutment structure for retaining the tube sheet upon its seat when there is an unbalanced pressure within the shell, at the under side of the tube sheet. The said abutment structure is releasable and removable from the channel to afford access to the leakage interception means and also to permit upward withdrawal of the tube sheet and its pendent bundle as a unit through the channel. While the invention is illustrated as embodied in a vertical heat exchanger unit, it may be employed satisfactorily in a unit otherwise disposed.

The structure of the unit includes a cylindrical

2

shell 1 closed at its lower end by a welded-on plate 2 and having at its upper end an outwardly extending welded-on flange 3. Adjacent its upper and lower ends respectively, the shell has an inlet nozzle 4 and an outlet nozzle 5. Beneath the nozzle 5 the shell has a cleanout nozzle 5a which is normally plugged. An L-shaped vent 6 leads from the interior of the shell outwardly through the flange 3 and downwardly to the under side of the flange.

At the upper end of the shell there is a channel or header structure. In the present instance said structure is detachably secured to the shell, but it may be welded on or otherwise secured.

15 This structure includes an annular body 7, of materially greater diameter than the shell and formed with outwardly extending flanges 8 and 9 at its upper and lower ends, respectively. A removable cover plate 10 is bolted, as at 11, to the flange 8, and the flange 9 is bolted, as at 12, to the shell flange 3, gaskets being interposed in said two joints. The channel body has inlet and outlet nozzles 13 and 14 respectively at points suitably spaced therearound. At the lower end thereof 20 the channel body is also formed with an inwardly extending annular flange 15 forming a shoulder or ledge for supporting the tube bundle.

25 The tube bundle includes a tube sheet 16 and a bundle of U-tubes 17 depending from the tube sheet into the shell. In lieu of U-tubes, however, straight tubes may be employed together with a floating head structure at the lower end of the bundle. The bundle of U-tubes bears a series of 30 staggered transverse baffles 18 arranged along the bundle between the shell nozzles 4 and 5. In Fig. 35 1 only a few of the tubes are shown, in order to simplify the illustration.

A countersunk seat 19 is formed in the ledge-forming flange 15 to receive the tube sheet. The 40 internal diameter of the flange 15 and that of the shell flange 3 corresponds to the internal diameter of the shell, the diameter of the tube sheet exceeds the internal diameter of the flange 15, and the margin of the sheet rests upon the bottom of the countersunk seat. The depth of the countersink is substantially equal to the thickness of the edge margin of the tube sheet so that the upper face of the sheet is substantially flush with the upper face of the flange 15, surrounding the 45 countersink. The countersink has an annular side wall 20 whose diameter materially exceeds that of the tube sheet to provide an annular space therebetween. Within this space there is a packing assembly forming part of the leakage interception feature. The packing assembly includes 50 55

a rigid spacing element in the form of a lantern ring 21 having annular grooves 22 in its circumferential faces, and a series of radial passages 23 spaced around the ring and connecting said grooves. Suitable packing is disposed above and below the lantern ring. In the present instance the packing at each side of said ring comprises a gasket ring 24 of rubber or other suitable compressible material. A vent passage or weep hole 25 leads from the packing space through the flanges 15 and 9 and is threaded at its outer end for attachment of piping to conduct off leakage intercepted by the packing assembly.

Within the channel or header an abutment ring 26 is bolted, as at 27, to the upper surface of the bottom flange 15, outwardly of the countersink. The abutment ring overlaps the margin of the tube sheet and serves to retain the latter upon its seat. At its under side said ring has a groove or channel 28 accommodating the upper portion of a gland ring 29 whose lower edge bears against the upper gasket ring 24 of the packing assembly. Screws 30 in threaded engagement with the abutment ring bear against the upper edge of the gland ring and are operable to force the gland ring downwardly and compress the packing assembly. These screws have check nuts 31 engageable with the abutment ring to maintain an adjustment of the screws. The gland ring tapers radially inward in cross section and the surfaces of said ring and the countersunk seat which engage the packing rings converge radially outward, to obtain effective compression of the packing rings against said surfaces and against the tube sheet and the lantern ring for a good sealing effect. The abutment ring and the gland ring are made in sections and the sections accommodate between them a pass partition 32 located between the header nozzles 13 and 14 and dividing the header into two compartments. The lantern ring and the compressible packing rings are each continuous. Each of the U-tubes of the bundle opens at one end into the compartment in communication with the inlet nozzle 13 and at its opposite end into the compartment communicating with the outlet nozzle 14. The lower edge of the pass partition is fitted within grooves formed in the upper face of the tube sheet and in the upper surface of the flange 7, and the side edges of the partition are fitted in grooves formed in the annular side wall of the header. The upper edge of the partition abuts the cover 10.

While its utility is by no means limited to that purpose, the unit was designed more particularly for cooling lubricating oil conducted from a turbine or other mechanism. In such service the unit will be mounted upon the top of a tank, indicated at T, with the shell depending into the tank. Water or other cooling fluid will be passed through the header nozzle 13 and the tubes of the bundle and discharged through the nozzle 14. Oil to be cooled will be passed through the upper shell nozzle 4 and thence downwardly over the cooling tubes and out through the nozzle 5 which discharges into the tank surrounding the shell. If desired, the flow of cooling fluid may be reversed so that the fluid will enter the shell through the nozzle 5 and leave through the nozzle 4. Cooled oil will be passed from the tank to the turbine or other mechanism to be lubricated. The vent 6 in the shell flange places the upper end of the shell in communication with the tank and prevents an accumulation of vapor within the shell which might prevent adequate charging thereof.

Leakage from either the shell or the header to the edge of the tube sheet is there intercepted by the packing assembly and passed out through the vent 25 so that intermingling of the shell-side fluid and the tube-side fluid is prevented. The abutment ring 26 serves to retain the tube sheet against upward displacement when the shell is subjected to high internal testing pressure for the purpose of detecting leakage at the joints between the tubes and the tube sheets. In addition to that, the abutment ring forms a mounting for the screws 30 for compressing the packing and serves to take the reaction of the compressing force applied by the screws.

The exchanger is designed for insertion and removal of the tube bundle through the header without the necessity of breaking any piping connections to the exchanger unit. For removal of the bundle the cover 10 and the pass partition 32 are removed and the abutment ring 26 is unbolted and removed through the upper end of the header. Thereby the gland ring is uncovered for withdrawal and the tube sheet is freed for upward withdrawal of the sheet and the bundle as a unit through the header. Removal of the abutment ring also renders the packing accessible for removal and servicing without the necessity of removing the tube sheet and bundle. When the parts are assembled the leakage interception means is entirely enclosed and protected from tampering so that the packing adjustment can be maintained.

It will be seen from the foregoing that our invention provides a very advantageous combination of a leakage interception feature and a tube sheet retaining feature. While we have disclosed a very satisfactory structural embodiment of the invention, it will be understood that the disclosure is merely illustrative and in nowise limiting and that the invention comprehends such modifications as will come within the scope of the following claims.

We claim:

1. Tube sheet mounting and sealing means for a heat exchanger of a type including a shell, a channel at one end of the shell and detachably connected thereto and a tube bundle with a tube sheet at the end thereof adjacent said shell end, and in which the shell and bundle are separable by relative movement therebetween longitudinally of the bundle and the bundle and said tube sheet are together removable through the outer end of the channel, said means comprising an annular inwardly extending flange borne by said channel at the end thereof adjacent the shell and having at its inner margin within the channel an annular inwardly facing countersunk seat for the margin of said tube sheet and an annular wall around the edge of the tube sheet and spaced therefrom and from the inner side wall of the channel, a packing assembly between the edge of the tube sheet and said wall including a lantern ring and packing at opposite sides of said ring, a vent in said wall and leading from the space occupied by said ring, a gland ring bearing against the packing at the outer side of said lantern ring, the packing at the inner side of the lantern ring bearing against said seat, an abutment ring within the channel overlapping the margin of the tube sheet and said flange and releasably secured to the portion of the flange between said flange wall and the inner wall of the channel to retain the tube sheet upon said seat, and screws in threaded connection with said abutment ring at points spaced therearound and

engageable with the gland ring to force the latter against the packing, said abutment ring, after release thereof from the flange, being removable through the outer end of the channel and the tube sheet being shiftable for removal past the packing assembly.

2. Tube sheet mounting and sealing means as claimed in claim 1 wherein the said abutment ring and the said gland ring are formed in sections to accommodate a pass partition of the channel between their sections.

3. Tube sheet mounting and sealing means for a heat exchanger of a type including a shell, a channel at one end of the shell and detachably connected thereto and a tube bundle with a tube sheet at the end thereof adjacent said shell end, and in which the shell and bundle are separable by relative movement therebetween longitudinally of the bundle and the bundle and said tube sheet are together removable through the outer end of the channel, said means comprising an annular inwardly extending flange borne by said channel at the end thereof adjacent the shell and having at its inner margin within the channel an annular countersunk seat for the margin of said tube sheet and an annular wall around the edge of the tube sheet and spaced therefrom and from the inner side wall of the channel, a packing assembly between the edge of the tube sheet and said wall including a lantern ring and packing at opposite sides of said ring, a vent in said wall and leading from the space occupied by said ring, a gland ring bearing against the packing at the outer side of

said lantern ring the packing at the inner side of the lantern ring bearing against said seat, abutment means within the channel overlapping the margin of the tube sheet and said flange and releasably secured to the portion of the flange between said flange wall and the inner side wall of the channel to retain the tube sheet upon said seat and screws in threaded connection with said abutment means and engageable with the gland ring to force the latter against the packing said abutment means, after release thereof from the flange, being removable through the outer end of the channel and the tube sheet being shiftable for removal past the packing assembly.
